Patented July 3, 1917.

UNITED STATES PATENT OFFICE.

LOUIS ZIEGLER, OF LYNDHURST, NEW JERSEY, ASSIGNOR TO THE NATIONAL FIRE-
WORKS DISTRIBUTING COMPANY, OF BOSTON, MASSACHUSETTS, A CORPORATION
OF ARIZONA.

TOY PISTOL.

1,232,469.

Specification of Letters Patent. Patented July 3, 1917.

Application filed October 11, 1916. Serial No. 124,924.

To all whom it may concern:

Be it known that I, LOUIS ZIEGLER, a citizen of the United States, and a resident of Lyndhurst, county of Bergen, and State of New Jersey, have invented certain new and useful Improvements in Toy Pistols, of which the following is a specification.

This invention relates to an improved pistol and has especial reference to toy pistols which are supplied with strips of paper or similar material, which strips are usually coiled and placed in a chamber of the pistol, and which strips are also provided with caps which form protuberances on the strip, whereby the strip is fed, and the caps are successively exploded by the action of a hammer as each strip is fed intermittently.

This improved pistol is constructed so as to make it easy to insert the cap strip in the pistol, to protect the hand of the user so that there can be no danger of injury by flying fragments of burnt powder or paper, to direct the burnt or exploded part of the paper strip and also the smoke and noise of an explosion of a cap, out through the front end of the pistol, thus simulating the firing of a real pistol.

A further object of the invention is to provide a toy pistol in which the parts cooperate to make the firing of the pistol easy and in which the positive return of the parts to normal position, when the trigger is released, is assured.

A still further object of the invention is to provide a hammer-actuating part and a strip-feeding mechanism operated directly by the trigger and being of a construction that permits of an easy and proper return of the trigger to normal position when the trigger is released.

The invention is illustrated in the accompanying drawing in which one embodiment of my invention is illustrated.

In said drawing, Figure 1 shows a side view of the pistol with one of the side plates or cheek-pieces of the pistol removed to more clearly illustrate the interior construction. Fig. 2 is a section on line 2—2, Fig. 1. Fig. 3 is a perspective view with the anvil-carrying and reel-inclosing part swung to an open position to more clearly illustrate the interior of the pistol and also to show how a strip of caps is inserted in the pistol.

The casing of the pistol is preferably made of two cheek-pieces or side plates 10

and 11 of suitable conformation to simulate the appearance of a pistol, these cheek-pieces or side plates being usually cast and fastened together by any suitable means, such as the screw 12. The side plates have depending portions to form the handle part 13, and one of said members may also be provided with a trigger guard 14 which can project slightly underneath the member other than the one to which it is attached, 60 so as to give the trigger guard a position that is symmetrical in its relation to the body of the pistol. Near the front end of the pistol is pivoted a combined anvil and cover 15, the forward portion 16 forming 70 the anvil, being pivoted to the side plates, this being usually done by providing the cover or anvil with an opening 17 into which the studs 18 of the cheek-pieces project. The cover 15 projects rearwardly, having a back 75 19 depending therefrom, which back is provided at its bottom edge with a nose 20 and having, at the side thereof, a gripping and covering portion 21 which fits in the cut-away part 22 of the cheek-piece 11. A 80 spring 23 is arranged with one end 24 disposed so that it engages the nose 20 and is provided with a suitable finger-piece, as the button 25, by means of which it can be pushed in to release the cover 15. The 85 spring 23 is given a tension by passing it around a stud 26 on one of the cheek-pieces and then extending upward, being bent, as at 27, to pass around the rear end of the block 28, the projecting or free end 29 of 90 the spring being adapted to normally extend upward, as shown in Fig. 3, when the cover is raised, but being pressed downward so that it is given a tension when the cover is shut, as in Fig. 1. The cheek-piece 11 95 has a stud 30 thereon on which is placed the coiled paper strip 31 which has suitable caps 32 arranged at intervals thereon, the projecting part of the strip 31 passing beneath the substantially smooth, lower face 100 33 of the cover 15, said face 33 terminating in the front end as the lower face of the anvil 16. The trigger 34 projects through an opening 35 in the bottom of the casing 105 of the pistol and has a forwardly projecting arm 36 and a rearwardly projecting arm 37. The arm 37 is recessed as at 38 so as to clamp the end 39 of the spring 40, the free end 41 of which normally rests against the lower face of the free end 29 of the spring 110

23 in rear of the front end of said last mentioned spring, and is adapted to be forced forward to feed the paper strip, as will be described hereinafter.

5 The trigger and its arms are yieldingly held in normal position by a suitable spring, the form shown comprising a spring 42 which encircles the hub 43 of the trigger, bearing as at 44 against the casing of the 10 pistol and having its other end 45 bearing against a suitable stud 46 on the side of the arm 36. The trigger has pivotal pins 47 projecting from its opposite sides, these pins 47 riding in a slightly elongated slot 48, 15 and being normally held in the upper end of the slots 48 by reason of the spring 42 having one end 44 resting on the casing so that the tendency of the spring is to force the trigger upward, at the same time that 20 the end 45 of the spring has a tendency to swing the trigger to a normal position. A hammer 49 is pivoted, as by means of the studs 50, in the sides of the pistol and is adapted to be normally swung upward 25 against the bottom of the anvil 16 by a suitably placed spring 51 which, in the form shown, has one end engaging the stud 52 of the casing of the pistol, the other end of the spring engaging the under part of the shelf 30 or flat portion 53 of the hammer 49. The hammer is provided with a block 54 which is approximately triangular in shape and projects sidewise from the depending portion 55 of the hammer and is in line with the 35 downward path of travel of a finger 56 projecting from the end of the forward arm 36 of the trigger, the coöperation of these parts to move and trip the hammer being described hereinafter.

40 The operation of the pistol is as follows: The button 25 is pressed and releases the cover part 15 which is swung upward to the position shown in Fig. 3. Then the coiled part of the strip 31 is placed over the stud 45 30 and the free end is laid over the free end 29 of the spring 23, as shown at *a* in Fig. 3, and is held in position and prevented from dropping too far into the casing to interfere with the operation thereof, by reason 50 of the flat upper face of the part 53 of the hammer 49. The strip is now in position and the cover part 15 is swung to its closed position shown in Fig. 1, being held closed by reason of the end 24 of the spring 23 snapping over the nose 20 of the rear part 19 of the cover 15. When it is so swung to its closed position the cover 15 has its bottom face 33 in engagement with the strip 31 and the strip is thus provided with a 55 smooth surface upon which it can slide when it is fed forward. When the trigger 34 is pulled, the arm 37 is swung upward to the dotted position shown in Fig. 1, and this forces the spring 40 so that its end passes 60 beyond the spring end 29 and the end of the 65

spring 40 engages the strip 31 as soon as it passes beyond the end of the spring 23 and forces the strip 31 forward, this being permissible because at the same time the arm 37 moves upward the arm 36 moves downward 70 and begins to swing the hammer 49 away from the anvil 16 so that a clear space is provided for the forward movement of the strip 31. When the forward arm 36 of the trigger has reached the position shown in 75 dotted outline in Fig. 1, the finger 56 passes beyond the forward edge of the block 54 and the hammer is released, this release taking place at the time that the spring 40 has succeeded in moving the strip forward 80 far enough to place the cap next to be fired in position under the anvil 16. The hammer 49 is then snapped shut by the spring 51 and the cap is exploded. The products of combustion incidental to the explosion, and any flash accompanying the explosion, pass out through an opening 57 in the front part of the casing, which is that part of the frame corresponding to the muzzle of a pistol. When the pressure on the 85 trigger 34 is released, the arm 37 swings downward, carrying with it the spring 40, but the spring 40 does not cause the paper strip to be pulled backward on account of the spring having its forward end pointed 90 forward and being moved backward it easily slips over the paper, while the free end 29 of the spring 23 is in the position that forces its front edge to engage the paper strip 31 and hold it against retreating while the 95 spring 40 slides back to the position shown in full lines in Fig. 1. The arm 36 is swung 100 upward and swings freely until it engages the lower inner face 58 of the block 54, and it is then forced, by reason of the tension of the spring 42, to slide up along the under side of this block 54, the necessary clearance being provided by reason of the studs 47 sliding down in the elongated slots 48, thus permitting the forward or tripping 110 end of the arm 36 to resume its position above the block 54 preparatory to the next movement of the hammer by reason of the trigger being pulled.

The pistol described herein is subject to 115 modifications as to its details and the relative arrangement of the parts, but the embodiment shown herein illustrates a pistol embodying the advantages of my invention. The pistol is so constructed that when it is 120 closed with a strip of paper caps in the pistol, the caps can be fired without any danger of the person firing the pistol being injured by reason of any sparks or burnt paper or small specks of powder escaping to 125 injure the hand by means of which the pistol is operated. This makes the pistol safe for the user, and furthermore it does eject such particles away from the person using the pistol, thus simulating the firing of a 130

real pistol more closely than those types where the caps are exploded in the rear of the pistol adjacent to the hand.

The pistol furthermore embodies an advantage in that it is extremely easy to insert the coil of paper carrying the caps, the coil being placed over the stud 30 and simply being passed with its free end toward the forward part of the pistol, it not being necessary to thread or weave the strip through any parts of the mechanism, as is usually the case in magazine toy pistols of this kind. Furthermore, the trigger mechanism is compact, the feeding of the strip being done directly from one arm of the trigger and the swinging hammer being actuated directly from the other arm of the trigger, the construction also permitting the return of the trigger arm, that actuates the hammer, to its normal position without giving it any side motion.

It will be noted that the spring 23, formed and supported as it is, acts as a lower wall for the chamber in which the coil of cap-strip is placed, one extremity of the spring acting to hold the cover portion shut, and the other extremity acting to engage the strip to prevent its retreating when the strip-feeding spring is returning to its normal position.

Having thus described my invention, I claim:

1. A toy pistol comprising a casing having side walls open at the top and between which a cap-strip can be guided and fed, the casing having a handle portion with a coil-receiving chamber above it, a trigger, a hammer operated from the trigger, a feeding mechanism operated from the trigger, the hammer supporting the cap-strip at its forward end, and a cover part which when open uncovers the coil and the strip issuing therefrom and when closed having its bottom face acting as an anvil for the hammer and as a surface against which the feeding means operates.

2. A toy pistol comprising a body portion with a handle portion at the rear thereof, a trigger in front of the handle, the body portion having a coil-receiving chamber above the handle, a hammer forward of the trigger and operated from the trigger, and a cover part on the body portion and adapted to close the chamber and to have its bottom face form an anvil for the hammer.

3. A toy pistol comprising a body portion with a handle portion at the rear thereof, a trigger in front of the handle, the body portion having a coil-receiving chamber above the handle, a hammer forward of the trigger and operated from the trigger, a cover part on the body portion adapted to close the chamber and to have its bottom face form an anvil for the hammer, and a feeding mechanism on the trigger disposed so as to feed a

cap-strip along the under face of the cover part in rear of the anvil.

4. A toy pistol comprising a body portion with a handle portion at the rear thereof, a trigger in front of the handle, the body portion having a coil-receiving chamber above the handle, a hammer forward of the trigger and operated from the trigger, a cover part on the body portion adapted to close the chamber and to form an anvil for the hammer, a feeding mechanism on the trigger disposed so as to feed a cap-strip along the under face of the cover part, and a spring to hold the strip against retreating when the feeding mechanism is returning to its normal position.

5. A toy pistol comprising a body portion having a trigger and exploding and feeding mechanism operated from the trigger, said body portion also having a chamber to receive a coil, and a cover to close the body portion and having its inner face adapted to form a surface against which the exploding means and the feeding means operate.

6. A pistol comprising a body portion having a handle at the rear thereof, the body portion having a chamber above the handle to receive a coiled strip of caps, a trigger in front of the handle portion, the body portion having an opening in the front end to simulate the muzzle of a pistol, a cover for the body portion, said cover being adapted to close the chamber in the body portion and to provide an anvil adjacent to the opening in the casing, a hammer operated from the trigger and adapted to explode caps in the strip against the anvil, and means for feeding the strip of caps forward from said chamber toward the opening in the casing.

7. A toy pistol comprising a casing having a trigger adapted to rock therein, the trigger being yieldingly held in normal position by a spring, the trigger having a forwardly extending arm and a rearwardly extending arm, a cover on the casing forming an anvil at the front, a hammer swinging in the casing and adapted to engage the anvil, the hammer and the forwardly projecting arm of the trigger having coacting means for swinging and tripping the hammer, the casing having an opening at its front end adjacent to the anvil and disposed to simulate the muzzle of a pistol, a spring having its free end projecting forwardly and being adapted to be put under a tension when the cover is put into place so as to engage a paper strip to prevent its retreating, and a feeding spring supported on the rearwardly projecting arm of the trigger and having its free end adapted to slide on the under face of the first mentioned spring.

8. In a toy pistol, a casing, a cover hinged to the casing at one end, and a spring between the side walls of the casing, the

spring having one end engaging the cover to hold it shut, the other end of the spring having its free end engaged by the cover when the cover is shut, the side walls of the 5 casing, the cover and the spring forming a chamber for holding a strip of caps.

9. In a toy pistol, a casing, a cover hinged to the casing at one end, a spring between the side walls of the casing, the spring having one end engaging the cover to hold it shut, the other end of the spring having its free end engaged by the cover when the cover is shut, the side walls of the casing, the cover and the spring forming a chamber 10 for holding a strip of caps, and a button 15 projecting through the casing for forcing one end of the spring out of engagement with the cover.

10. In a toy pistol, a trigger having a 20 forwardly extending arm and a rearwardly extending arm, a spring-actuated hammer swung and tripped by the forward arm, a feeding spring secured to the rear arm, and a cover against which the hammer and feeding 25 spring operate.

11. In a toy pistol, a trigger having a spring to yieldingly hold it in normal position, the trigger having a forward arm and a rear arm, a hammer having a block thereon, a finger on the forward arm and adapted to bear on the block to swing and trip the hammer, a spring on the rear arm and having its free end inclined toward the hammer, and a cover against which the 35 hammer and the spring operate.

12. In a toy pistol, a casing, a trigger, the casing having elongated slots in its side walls, pivotal pins on the trigger extending into the slots, a spring bearing on the trig-

ger to hold it in one end of the slots and 40 also in normal position, a spring-actuated hammer having a block thereon, a forward arm, on the trigger, a finger on the arm to force the block downward and trip it by clearing it at a point in their travel, and an 45 anvil against which the hammer strikes when released.

13. A toy pistol comprising a casing having a chamber opening toward the top, a trigger mechanism with an upwardly inclined feeding device, an upwardly swinging hammer, the casing having an open top whereby a strip of caps can be placed in the chamber and laid on the hammer and over the feeding device, and a cover for closing 55 the chamber and forming an element against which the feeding device and the hammer operate.

14. A toy pistol comprising a casing having a chamber opening toward the top, a trigger mechanism with an upwardly inclined feeding device, an upwardly swinging hammer, the casing having an open top whereby a strip of caps can be placed in the chamber and laid on the hammer and over 60 the feeding device, a cover for closing the chamber and forming an element against which the feeding device and the hammer operate, and a spring having one free end adapted to engage the cover to prevent backward movement of the strip and having its other end formed into a snap to hold the cover in place.

In testimony that I claim the foregoing, I have hereto set my hand, this 10th day of 75 October, 1916.

LOUIS ZIEGLER.
